United States Patent Office

Des. 178,490

Patented Aug. 14, 1956

178,490

PLATE HOLDER

Thomas A. Blizzard, Black Mountain, N. C., assignor of fifty per cent to James A. Dougherty, Black Mountain, N. C.

Application August 17, 1955, Serial No. 37,534

Term of patent 14 years

(Cl. D33—3)

Figure 1 is a perspective view of a plate holder embodying my new design, illustrating the front and one side thereof;

I claim:

The ornamental design for a plate holder, substantially as shown.
